AUTOMATICALLY OPERATED VALVE
MECHANISMClarence J. Ruzicka, Whittier, Calif., assignor to
Standard Oil Company of California, San
Francisco, Calif., a corporation of Delaware

Application December 19, 1933, Serial No. 703,102

10 Claims. (Cl. 137—68)

This invention relates to a valve mechanism, and more particularly to a valve mechanism of the automatic type having improved control means for the regulation of the level of liquids contained in storage tanks or other receptacles.

It is known that valve mechanisms of the general class in which the present device is associated have heretofore been proposed; however, all such mechanisms hitherto known, especially of the electrically operated type, are undesirable and dangerous when used in connection with combustible liquids or fluids. All of these proposed mechanisms that are in any way analogous to the present device employ one or more of the fluids, whose level it is desired to regulate, as an electrical conductor, and when any one of such fluids is of a volatile nature, the danger of fire or an explosion may be present due to sparking when the operating current is broken at the connection with the fluid conductor. Further, all these proposed mechanisms require a high operating current in the presence of the liquid being regulated and aside from the fire hazard and rapid electrolytic consumption of the electrodes employed with the fluid conductors, the operation of the mechanisms soon becomes undependable.

Also, all of the devices heretofore proposed are undesirable due to the lack of means for changing the level at which the liquid under control is to be maintained, which is often desirable. In these devices it is necessary to drain the tank containing the liquid, remove certain parts and substitute others or to change the location of the device entirely.

It is one object of this invention to overcome the above difficulties.

Another object is to provide a novel valve mechanism having improved automatic control means.

Another object is to provide a novel valve mechanism having improved electrical control means that shall be operable by fluids of small variations in electrical conductivity.

Another object is to provide a novel electrical valve mechanism for regulating the level of fluids possessing different electrical characteristics that will be operable by current variations.

Another object is to provide a valve mechanism of the automatic type for controlling the level of fluids of different electrical characteristics that shall be operable by a minimum amount of control current in the presence of the liquid being controlled and thereby render the device for use with fluids of a volatile nature.

Another object is to provide a valve mechanism of the electrical type for use in controlling the level of combustible fluids that shall be operable by current variations and thereby preclude the necessity of completely breaking the current in the presence of the fluid being controlled.

Another object is to provide a valve mechanism having the above characteristics adapted to be controlled by a fluid whose level is to be controlled that shall be responsive to small current variations and adaptable for use with fluids having small variations in electrical characteristics.

Another object is to provide a device having the above characteristics that may be operable by fluid conductors and that shall be independent of wide variations in electrical resistance of the fluid conductors.

A further object is to provide in combination with a tank or container adapted to contain one or more fluids whose levels are to be controlled, a device having the above characteristics that shall be easily and quickly adjusted for maintaining the liquid levels or the limits of the liquid levels at or between predetermined point or points.

The accomplishment of the above and other objects by the novel combination of circuits and elements will be apparent to those skilled in the art from the following description when taken in connection with the accompanying drawing wherein reference characters are used to indicate the different parts. It is to be expressly understood that the drawing is not a definition of the invention, but merely one form to illustrate how the principles of the invention may be effectuated.

The drawing is a single view showing a schematic diagram embodying the invention.

In the form shown, 11 is a metallic tank or container which may be of any selected size and for the purpose of this disclosure, it will be sufficient to assume that the tank 11 is employed to contain two fluids of different specific gravities, 45 which may be oil and water. The tank 11 is provided with a drain pipe or bleeder line 12, the latter being connected with the tank at a point 10 adjacent the tank bottom 13. The bleeder line 12 has connected therein, in addition to a manually operated valve 14 and strainer 15, an electrically operated valve 16, the latter being operated by an electric coil or motor 17 of any approved type. Electric current is supplied to the coil 17 by way of a branch operating circuit 18 55

from an alternating current supply circuit 19. The circuit 18 is controlled by a coil operated switch 21, the latter being connected in a branch circuit 22 from the circuit 18.

5 The coil circuit 22 is also under control of a magnetic relay or coil operated switch 23. The relay 23 is of a sensitive direct current type and is connected in an actuating or control circuit 24, supplied with current from the terminals 25 of a 10 suitable rectifier 26, the latter having its terminals 27 fed from the alternating current supply circuit 19 by way of a selected transformer 28. The small transformer 28 reduces the alternating current to the proper value for application 15 to the rectifier 26. A suitable resistor 29 is connected across the circuit 24 to provide sufficient load to secure proper operation of the rectifier 26.

The neutral side of the control circuit 24 is 20 grounded at 9 to the tank 11, when the tank 11 is of electrical conducting material, or the circuit 24 may be connected to an electrode 9a carried by the lower portion of the tank wall and extending into the tank for contacting the liquid, when 25 the tank is constructed of non-conducting material. The other side or positive side of the circuit 24 which is connected through the sensitive relay switch 23 is also connected through a resistor 31 to an electrode 32 suspended within the tank 11. 30 and at a predetermined level within the tank 11. A second resistor 33 is employed across the circuit 24 which serves as a discharge resistor for keeping the direct current circuit through the relay 23 continually closed but will not pass sufficient current to operate the relay 23. It might 35 be well to state here that the amount of current required to operate the relay 23 is .0008 amperes.

The positive side of the control circuit 24 divides at 34 forming a second circuit 35. The 40 latter passes through a resistor 36 to a second electrode 37 suspended within the tank 11 and at a predetermined level within the tank, which level is lower or nearer the bottom of the tank than the level at which the electrode 32 is positioned.

The circuit 35 also divides at 38 forming a third circuit 39. The latter passes through a resistor 41 to a third electrode 42 suspended within the tank 11, and at a predetermined level within the tank, which level is still lower or nearer the bottom of the tank than the level at which the electrode 37 is positioned.

The electrodes 32, 37 and 42 together with their respective conductor leads disposed within the tank 11 are supported by and arranged within a conduit or pipe 30. The latter may be inserted from the top of the tank 11 and supported as shown at 44. It will be understood, of course, that the electrodes and their cooperating multiple circuit leads are electrically insulated from the conduit 30 and tank 11. This enables the level at which the fluid is controlled to be easily varied by moving the conduit 30 up or down with respect to the top of the tank 11 and supporting 60 means 44 without draining the tank. This is an important feature of the present invention and greatly simplifies the adjusting of the level at which the liquid is to be maintained. Heretofore, it has been necessary to drain the tank, 65 as well as to require the installation of additional parts and the repositioning of other parts.

The operation of the device is as follows:

Assuming that the tank 11 is adapted to receive a mixture of any two fluids possessing sufficient differences in density as to cause them to

be separated by gravity and which fluids differ in electrical conductivity, such as oil and water, and it is desired to control the level of the water under the oil. In the accompanying drawing 40 indicates the settled water and 41 indicates the 5 oil supported above the water. In actual practice, the water and oil would most generally be separated by a layer of emulsion. However, for the purpose of the present invention it will be sufficient to consider the emulsion layer as a part 10 of the water and it is included in the defining of the water level, as such emulsion usually contains water and sufficient salts to render its electrical characteristics substantially the same as water, or at least near enough to satisfy the purpose here 15 required.

It will be understood that the presence of the oil or second fluid is not required for proper operation of the device, but when and if a second fluid is present, the only requirement being that 20 it possess different characteristics in electrical conductivity.

The lowermost electrode 42 terminates at a point lower than the minimum level, indicated by the line 43, at which the water is to be maintained in the tank. By having the electrode 42 positioned below the minimum level of the water conductor 40, the latter remains charged at all times through a complete control circuit from the terminals 25 of the rectifier 26, which current, however, is insufficient to operate relay 23. This circuit includes the following electrical connections, positive side of circuit 24 from rectifier terminal 25 through relay 23 and resistor 31 to branch connection 34, circuit 35, resistor 36 to 35 connection 38, circuit 39 through resistor 41 to electrode 42, water 40 through tank 11 to ground 9 and returned by way of the neutral side of control circuit 24 to rectifier 26. When the level 43 of the water 40 rises sufficient to contact the 40 electrode 37, the branch circuit 39 and resistor 41 is shunted out by electrode 37, which increases the amount of current through relay 23, but which current is still insufficient to operate relay 23. The level 43 of the water may continue 45 to rise until it contacts electrode 32, at which time the branch circuit 35 and resistor 36 is also shunted by 32, and sufficient current may pass through the control circuit 24 to close relay 23 for closing the branch circuit 22, the latter energizing relay 21 for closing operating circuit 18, the latter energizing coil or motor 17 for opening the valve 16, at which time the water is drawn out by way of the pipe 12. As soon as the level 50 43 of the water moves below and out of contact with the electrode 32, the control circuit will again depend largely on branch circuit 35, resistor 36 and electrode 37. The resistor 36 acts to reduce the current in the control circuit 24, which current while insufficient to operate the 60 relay 23 is sufficient to hold it closed, and thereby effect a holding circuit for retaining the valve 16 open. The water continued to drain out through the pipe 12 until such time that the water level 43 falls below and out of contact with 65 the electrode 37, at which time the control circuit will depend entirely on branch circuit 39 and resistor 41, the latter acting to reduce the control current to an amount insufficient to hold the relay 23 closed. The relay 23 will now assume its normal open position, de-energizing circuit 22, opening relay 21, de-energizing operating circuit 18 and coil or motor 17 for closing the valve 16. The water level 43 rises and the operating cycle is repeated.

For disclosing a preferred form of the present device, it was elected to employ direct current in the control circuit because of the inherent sensitiveness and positiveness of operation in direct current magnetic relays. However, it is here pointed out that by substituting suitable equipment, the present device may be operated directly from either a direct current or alternating current source.

10 Accordingly there is provided a novel liquid control device that is automatic and positive in operation including novel electrical control means wherein the device is operated by varying the current passing through the control circuit, 15 which circuit includes the liquid whose level is to be controlled and the complete breaking of the control circuit in the presence of the liquid being controlled is precluded, thereby eliminating the hazard of fire or explosion and rendering the present device particularly adaptable 20 for use in controlling the level of liquids of a combustible nature.

Also, the importance of the manner in which the position of the electrode may be easily and 25 readily adjusted to maintain the liquid levels at or between any desired point or points is thought to be a valuable contribution to this particular art.

While the present device has been disclosed in 30 connection with the controlling of the levels of water and oil, it will now be apparent to those skilled in the art that the present device may be readily used for accurately controlling the level of any fluid for which electrical resistance is not 35 so high as to render it inoperative. Also, it is to be expressly understood that the present invention may be employed to control either the outlet or inlet of fluids. Other changes, modifications, substitutions, additions and omissions 40 may be made without departing from the spirit and scope of the claims hereto appended.

I claim:

1. In combination with a tank adapted to contain a liquid and provided with an outlet, an 45 electrically operated valve for controlling said outlet, a source of electrical energy, an electrical circuit of graduated resistance including said liquid in said tank for controlling the operation of said valve, means for maintaining and limiting a continuously flowing current in said circuit insufficient to cause said valve to be operated and another means dependent upon the level of said liquid for increasing said continuously flowing current through said 50 liquid sufficient to cause said valve to be operated.

2. In combination with a tank adapted to contain a liquid and provided with an electrically controlled outlet, of means for controlling said outlet for controlling the level of the liquid in 55 said tank, said means including means for maintaining a continuously flowing current through the liquid in said tank and adapted to vary the strength of said continuously flowing current sufficiently to operate said outlet when said liquid rises to a predetermined level.

3. In combination with a tank adapted to contain a liquid and provided with an automatic controlled outlet, electrical means including a cir-

cuit and a source of electrical energy, said circuit including the liquid in said tank and adapted to maintain a limited current through said liquid, another circuit in multiple with the first said circuit and dependent upon the level of the liquid 5 for increasing the amount of the first said current through said liquid.

4. In combination with a tank adapted to contain a liquid, of means for controlling the level of said liquid in said tank, said means including 10 electrical means for maintaining a limited current through said liquid, and another means in multiple with said last named means for increasing the strength of said current sufficient to operate the first said means when the level of said liquid 15 rises to a predetermined height within said tank.

5. A container adapted to contain a liquid having means for controlling the level of said liquid including means for maintaining a limited electrical current through said liquid independent 20 of the level of said liquid, and another means in multiple with said last named means dependent upon the level of said liquid for varying the strength of said current through said liquid.

6. In combination with a tank adapted to contain a liquid electrically operated means for controlling the level of said liquid, a source of electrical energy, the first said means including means for maintaining a continuously flowing current through said liquid, and means dependent 30 upon the liquid level for varying the amount of current through said liquid, whereby the first said means will operate without completely breaking said current in the presence of said liquid.

7. In combination with a tank adapted to contain an electrically non-conducting fluid overlying an electrically conducting liquid, an outlet for said conducting liquid, a valve for controlling said outlet, a plurality of vertically spaced electrodes in said tank, and electrical control means 40 for said valve, said means comprising multiple electrical circuits, each connected to one of said electrodes, whereby the lowest of said electrodes will continuously be in contact with said conducting liquid to permit a limited current to flow 45 therein, and the highest of said electrodes, when said conducting liquid is in contact therewith, will increase the said limited current to a value which will cause said valve control means to operate to drain said conducting liquid from said tank. 50

8. A combination according to claim 7, in which said multiple electrical circuits are of progressively cumulative resistance, that to the lowest electrode being the highest resistance.

9. A combination according to claim 7, with 55 the addition of means for simultaneously adjustably positioning said electrodes in said tank.

10. A combination according to claim 7, in which there are more than two branch electrical circuits connected, respectively, to a like number of vertically spaced electrodes, an intermediate electrode circuit being adapted to maintain said limited current to a value adequate to cause said valve to remain in an open position after being once opened, but inadequate to cause said valve to be actuated from a closed to an open 60 position. 65
